UNITED STATES PATENT OFFICE

161,722

MOLDED BUILDING BLOCK

William J. Waller, Bridgeport, Conn.

Application June 30, 1949, Serial No. 3,639

Term of patent 14 years

(Cl. D18—2)

To all whom it may concern:

Be it known that I, William J. Waller, a citizen of the United States, residing at Bridgeport, county of Fairfield, State of Connecticut, have invented a new, original, and ornamental Design for Molded Building Block, of which the following is a specification, reference being had to the accompanying drawing, forming a part hereof.

Fig. 1 is a top plan view of a building block, showing my new design;

Fig. 2 is an end view thereof, and

Fig. 3 is a front view.

I claim:

The ornamental design for a molded building block, substantially as shown.

WILLIAM J. WALLER.
